Specification for Design.

Patented May 31, 1921.

Application filed April 23, 1920. Serial No. 376,152. Term of patent 14 years.

To all whom it may concern:

Be it known that I, JOHN E. LANGSTAFF, a citizen of the United States, and resident of the borough of Brooklyn, in the city and State of New York, have invented a new, original, and ornamental Design for a Boat-Hull, of which the following is a specification, reference being had to the accompanying drawing, forming part thereof.

My new design for a boat-hull is shown in the accompanying drawing, in which—

Figure 1 represents a top plan view of a boat-hull showing my new design.

Fig. 2 represents a side elevation of the same.

Fig. 3 represents a front elevation of the same.

Fig. 4 represents a rear elevation of the same, and

Fig. 5 represents a bottom plan view of the same.

I claim:

The ornamental design for a boat-hull substantially as shown.

JOHN E. LANGSTAFF.
